UNITED STATES PATENT OFFICE.

EMMANUEL LAVALLEE, OF PAWTUCKET, RHODE ISLAND, ASSIGNOR TO SHAMBOW SHUTTLE COMPANY, OF WOONSOCKET, RHODE ISLAND, A CORPORATION OF RHODE ISLAND.

SHUTTLE.

Application filed January 12, 1923. Serial No. 612,193.

To all whom it may concern:

Be it known that I, EMMANUEL LAVALLEE, a citizen of the United States, residing at Pawtucket, in the county of Providence and 5 State of Rhode Island, have invented certain new and useful Improvements in Shuttles; and I do hereby declare the following to be a full, clear, and exact description of the invention, such as will enable others 10 skilled in the art to which it appertains to make and use the same.

The present invention relates to an improvement in shuttles.

In many mills today there are in use both 15 plain and automatic looms, and it is obviously a matter of economy that bobbins adapted for use in the automatic looms should sometimes be used in plain looms, so that bobbins as they come along may be 20 used either in the plain or automatic looms as occasion of convenience demands. The ordinary plain loom is provided with a different shuttle from that employed in the automatic looms and one not ordinarily 25 adapted for use in holding bobbins adapted for use in the automatic looms.

The object of the present invention is to produce a shuttle for use in plain looms 30 having features of construction adapting it for convenient use with bobbins ordinarily used in shuttles of automatic looms. To this end the present invention consists in the shuttle for plain looms hereinafter described and particularly defined in the claims.

35 In the accompanying drawings illustrating the preferred form of the invention, Fig. 1 is a plan of the shuttle; Fig. 2 is a section taken on the line 2—2, Fig. 1; and Fig. 3 is a longitudinal section of the right-hand 40 end of the shuttle shown in Fig. 1.

The illustrated embodiment of the invention is described as follows: The shuttle 10 is provided with an eye 12 of any usual or convenient form used for plain looms. The 45 bobbin holder consists of a spring 14 having the usual jaws provided with grooves 16 for receiving the rings 18 of the bobbin 20. The bobbin holder is provided with a guide 22 of the usual form except that it is slotted at its front end to receive the bobbin pin 24 pivoted at 26 on the bolt 28. The bobbin pin 24 is recessed at 30 so that when it is 50 swung upwardly, as shown in broken lines

in Fig. 3, the edge of the guide 22 and of the top plate 32 will be received in the 55 notch. The guide 22 is secured to the shuttle by the screw 34 in the usual manner. The bottom plate 36 of the guide 22 extends under the bobbin spring 14, and the plate 32 rests upon its upper surface, such bottom 60 plate and plate 32 being received in grooves in the shuttle and held in place by the screw 34 and the bolt 28.

In operation the bobbin pin 24 is raised to the position shown in broken lines in 65 Fig. 3, the bobbin is thrust on it, and then pressed downward, the bobbin acting as an extension of the lever of the bobbin pin, affording a convenient lever means for 70 forcing the bobbin butt between the jaws of the bobbin spring, where it will be held in place by the spring. The bobbin will be thrust down on the bobbin pin until the end 75 of the bobbin strikes the guide, and then as the pressure is exerted upon the bobbin, it will be pushed outwardly on the bobbin pin by the slide, and will enter the space between the jaws of the bobbin spring.

The two sides of the guide not only afford guiding means to guide the bobbin 80 down into the shuttle, but they also serve as a support and guide for the bobbin pin so that the latter is adequately controlled in its position in the shuttle. The bobbin pin, it will be observed, does not control the 85 position of the bobbin in the shuttle. It consists in the present shuttle merely of a device for assisting the operative to insert the bobbin in the shuttle. The bobbins, it will be observed, are as well adapted for use 90 in automatic looms as in plain looms, and inasmuch as bobbins are much more numerous than the shuttles, it is a convenience and economy to adapt the shuttle of the plain loom to receive the bobbin of the automatic, 95 rather than to use a special bobbin for the plain looms. In other words, ordinarily both the bobbins and the shuttles are required to be especially adapted for the plain looms, and the present invention eliminates 100 the necessity of adapting both to this loom, as the shuttle alone is made special.

Having thus described the invention, what is claimed is:

1. A shuttle for plain looms having an 105 eye and a bobbin holder, the latter com-

prising a stationary double jawed bobbin spring of the Northrop loom type and a pivoted bobbin pin, and a bolt for holding the shuttle spring in place in the shuttle and constituting the pivot for the bobbin pin.

2. A shuttle for plain looms having an

eye and a bobbin holder comprising a bobbin spring provided with two bobbin holding arms, a butt guide provided with a medial groove, a bobbin pin received in the groove in the guide, and a bolt for securing the bobbin spring and bobbin pin in place.
